UNITED STATES PATENT OFFICE

2,464,953

PIVOTED OUTER JAW WRENCH HAVING
FULCRUM DETENT QUICKLY SHIFTABLE
ALONG HANDLE RACK

Nathan W. Warman, Los Angeles, Calif.

Application February 27, 1946, Serial No. 650,488

1 Claim. (Cl. 81—106)

1

This invention relates to a wrench, and while features of the invention are applicable in the construction of a wrench for rotating a nut or a bolt head, the invention is particularly applicable in the construction of a wrench for gripping a round object such as a pipe, that is to say, to perform the function of a wrench of a type popularly known as a Stillson wrench.

An object of the invention is to attain the objects indicated above, by a construction which will enable the relatively movable jaw of the wrench to be quickly brought to a position to grasp the round object or pipe, by a very simple operation readily performed while the wrench is held in its operator's hands.

Another object of the invention is to provide a wrench of this type in which the wrench will tighten itself automatically through the action of the torque force being applied to the handle or lever of the wrench, and which will automatically loosen itself when the force is reversed, as it would be when the wrench was being rotated back into a new position to enable the jaws to take a new grip on a pipe or other round object that is being rotated against a resistance.

Another object of the invention is to produce a wrench capable of functioning as described, but which is constructed of few parts of simple form, which can be very economically manufactured and readily assembled to form the complete wrench.

Further objects of the invention will appear hereinafter.

The invention consists in the novel parts and combinations of parts to be described hereinafter, all of which contribute to produce an efficient wrench.

A preferred embodiment of the invention is described in the following specification, while the broad scope of the invention is pointed out in the appended claim.

In the drawing:

Fig. 1 is a view in elevation, taken partly in section on the line 1—1 of Fig. 2, and shows a longitudinal section through the wrench head and through a pipe to which the wrench is illustrated as applied, the movable jaw and the handle carrying the same, being indicated in side elevation with the outer portion of the handle broken away.

Fig. 2 is a plan of the wrench shown in Fig. 1, the outer portion of the handle being broken away.

Fig. 3 is a view similar to Fig. 1, but with the outer portion of the shank of the handle broken

2

away. This view shows the wrench in a released position in which the shank of the wrench is disconnected from a cooperating part to permit the movable jaw and its shank to be moved readily toward or from the relatively fixed jaw of the wrench.

Referring to Figs. 1 and 3, the wrench preferably includes a wrench head 1 which preferably has substantially the form indicated, that is to say, the wrench head presents a throat 2 opening into it from one side, and this throat is formed between a relatively fixed outer leg portion, or jaw 3 and a guide extension 4 which operates as a guide for the relatively movable jaw of the wrench. The movable jaw 5 that cooperates with a serrated face 6 of the movable jaw, is preferably formed as the end face of the shank 7 of a handle or lever 8 to which the force is applied in order to enable the movable jaw 5 to clamp an object such as a pipe 9 between the two jaws. This jaw 5 is preferably formed as a serrated face disposed in a plane that is inclined to the longitudinal axis of the shank 7. In accordance with my invention, this jaw and the shank 7 are guided on the guide extension to enable the shank 7 to be shoved inwardly so as to approach the relatively fixed jaw 3, and also in accordance with my invention I provide means associated with the guide extension 4 to resist a backward movement of the shank 7 after the jaw 5 has been brought into contact with the object such as the pipe 9 that is to be rotated. In order to accomplish this, I prefer to form the extension 4 with a deep slot 10 that extends into the same from its outer end and throughout its entire length, the inner end of the slot 10 being extended into the neck 11 that operates to connect the fixed jaw 3 integrally to the guide extension 4. This slot 10 is of uniform width of course, and the side faces between which the slot is formed, rest against the side faces of the shank 7. This shank is of rectangular cross-section.

By reason of the presence of the slot 10, of course the inner leg or extension 4 is formed into two forks 12 of plate-like form, and between these forks and in the slot 10, I provide means for engaging the adjacent edge of the shank 7. In the present instance, this means consists of a burr or block 13, and this burr and the adjacent side 45 of the shank 7 have a correlated form which enables the burr to resist outward thrust in the shank when these parts are in engagement with each other. In the present instance, I form rack teeth 14 along the outer edge of the shank 7, 50 and I employ a burr 13 of substantially semi-

circular form but presenting a serrated edge 15 formed with transverse rack-teeth of the same pitch and size as the rack-teeth 14. These teeth 14 and the teeth of the serrated edge 15 have the form of ratchet teeth, that is to say, each tooth presents an inclined face 16 inclined with respect to the direction in which the line of teeth extend, the other edge 17 of each tooth being at right angles to the edge along which the teeth extend. In this way, these faces 17 present abrupt shoulders to engage each other so as to resist movement of the shank 7 away from the jaw 3 when the teeth of the shank are in engagement with the teeth of the burr. However, by reason of the fact that the engaging teeth are inclined, it will be evident that the shank 7 can readily be moved inwardly because the inclined faces of the teeth will simply slide freely over each other. By reason of this fact, the jaw 5 can be readily shoved forward to engage the side of the pipe 9, as indicated in Fig. 1. When in this position, it will be evident that if a force is applied at the point indicated by the arrow 18 to pull the handle 8 forwardly, the jaw 5 will grip the pipe 9 and press it forcibly against the face of the jaw 3. However, as soon as this force acting on the point 18 is reversed, the jaw 5 will loosen up its grip and the handle then can be swung back or upwardly as viewed in Fig. 1, to bring it to a new starting position, whereupon by a second movement in the direction indicated by the arrow at 18, the jaws will tighten up again and the pipe 9 can be rotated through another angle of rotation. In this way, a ratchet movement can be developed in using this wrench, that is desirable.

The burr 13 is mounted to rock on an axis on the extension 4, and for this purpose I prefer to provide a transverse pivot pin or bolt 19 that passes through the burr, and has its ends secured in the side plates or forks 12 of the head.

The wrench is preferably provided with means for yieldingly pressing the shank 7 toward the burr 13 so that the teeth of the shank and the burr are normally maintained in engagement with each other. However, as illustrated in Fig. 3, by moving the shank 7 toward the neck 11 of the wrench head, the engaging teeth can be disengaged from each other. This movement is resorted to whenever it is necessary to free the extension 7 with its movable jaw 5 to permit the jaw 5 to be opened up to receive a pipe of larger diameter. For this purpose I prefer to provide a coil spring 20 mounted in the slot 10, and the coil of this spring can be very readily mounted on a transverse bolt or machine screw 21, the forward end of which is provided with screw threads, and the outer end of which is provided with a screwdriver notch for tightening up the threads. This is illustrated in dotted lines in Fig. 2. This spring 20 has a bifurcated tongue 22 to thrust against the rear edge or rear side 23 of the shank, and the spring is provided with a tail 24 that thrusts against an inclined face 25

that forms the bottom of the slot 10 in the neck 11. In order to prevent the shank 7 from being pulled accidentally out of the slot 10, I prefer to provide a small transverse drilled hole near the end of the shank 7 to receive a small split pin 26 as indicated in Fig. 1.

It will be evident that this wrench head 1 can be very readily constructed of hard steel or alloy metal which will insure that the teeth of the 10 jaw 3 will resist the very high pressure that is developed when the lever 8 of the wrench is pulled in the direction to tighten the jaws.

The shank 7 and its jaw 5, of course should be constructed of hard steel or alloy metal for the same purpose.

Many other embodiments of the invention may be resorted to without departing from the spirit of the invention.

I claim as my invention:

20 In a wrench, the combination of an integral U-shaped wrench head having inner and outer leg portions and a connecting web portion, a rigid jaw on said outer leg portion, a continuous longitudinal guide slot in said head extending from the free end of said inner leg portion to its other end and into said connecting web portion, a detent block mounted within said slot adjacent the free end of said inner leg portion, a handle with a shank having front and rear sides, and two flat sides for guided movement in said slot, said shank having an end face forming a jaw surface confronting said rigid jaw to cooperate with the same to clamp an object therebetween, a pin extending across said slot near the free end of said inner leg portion and pivotally mounting said detent block therein to rock on an axis normal to the plane of said U-shaped head, said detent block having rack-teeth formed on the side thereof adjacent said front side of the shank, said front side of the shank having corresponding rack-teeth to engage the rack-teeth of the block, a pin extending across the web portion of said slot beyond the rear side of said shank, and a spring mounted on said last named pin and exerting pressure on said shank to urge the same toward the block; the web portion of said guide slot providing an unobstructed space back of said shank permitting said shank to be moved back at all times to disengage its teeth from said detent block.

NATHAN W. WARMAN.
